US0D1101939S

(12) **United States Design Patent** (10) **Patent No.:** **US D1,101,939 S**
(45) **Date of Patent:** **** Nov. 11, 2025**

(54) **CRADLE**

(71) Applicant: **EDWARDS LIFESCIENCES CORPORATION**, Irvine, CA (US)

(72) Inventors: **Jacob White Sullivan**, Mission Viejo, CA (US); **Ismail Thazhapilavil**, Irvine, CA (US); **Robert Bowes**, Trabuco Canyon, CA (US); **Matthew Paul Dwight**, Laguna Beach, CA (US)

(73) Assignee: **EDWARDS LIFESCIENCES CORPORATION**, Irvine, CA (US)

(**) Term: **15 Years**

(21) Appl. No.: **29/983,479**

(22) Filed: **Jan. 10, 2025**

Related U.S. Application Data

(62) Division of application No. 29/878,892, filed on Jun. 28, 2023, now Pat. No. Des. 1,071,198.

CLAIM

The ornamental design for a cradle as shown and described.

DESCRIPTION

FIG. 1 is a first perspective view of a cradle of the new design;

FIG. 2 is a second perspective view of the cradle of FIG. 1; FIG. 3 is a front elevational view of the cradle of FIG. 1; FIG. 4 is a rear elevational view of the cradle of FIG. 1; FIG. 5 is a left side elevational view of the cradle of FIG. 1, the right side elevational view being a mirror image thereof; and,

FIG. 6 is a top plan view of the cradle of FIG. 1. The broken lines are included for the purpose of illustrating portions of the article and form no part of the claimed design.

1 Claim, 5 Drawing Sheets
